CLAIM

The ornamental design for a collapsible syringe holder, as shown and described.

DESCRIPTION

FIG. 1 is a perspective view of a collapsible syringe holder, the broken line illustrating environment only and forming no part of the claimed design;

FIG. 2 is a left end view thereof, the right end view being a mirror image thereof;

FIG. 3 is a top plan view thereof;

FIG. 4 is a rear elevational view thereof;

FIG. 5 is a front elevational view thereof;

FIG. 6 is a bottom plan view thereof;

FIG. 7 is a perspective view of an alternate embodiment of the collapsible syringe holder;

FIG. 8 is a left end view thereof, the right end view being a mirror image thereof;

FIG. 9 is a top plan view thereof;

FIG. 10 is a rear elevational view thereof;

FIG. 11 is a front elevational view thereof; and

FIG. 12 is a bottom plan view thereof.
